(57) **CLAIM**

The ornamental design for automobile tire tread, as shown and described.

DESCRIPTION

FIG. 1 is a front view of an automobile tire tread, showing the new design, a top plan view thereof, a bottom plan view thereof appearing the same as the front view;

FIG. 2 is a rear view of the automobile tire tread;

FIG. 3 is a right side view of the automobile tire tread;

FIG. 4 is a left side view of the automobile tire tread;

FIG. 5 is a fragmentary front view, showing in enlargement the portion of V—V in FIG. 1;

FIG. 6 is a cross-sectional view, taken along line VI—VI and in the direction of arrows in FIG. 5; and,

FIG. 7 is a perspective view of the automobile tire tread. The broken line showing of a tire sidewall and inner bead, and the peripheral boundary between the tire tread and sidewall, indicate unclaimed environment and form no part of the claimed design.
